(57) **CLAIM**

The ornamental design for a portable notebook screen splitter, as shown and described.

DESCRIPTION

FIG. 1 is a front perspective view of a portable notebook screen splitter showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof;

FIG. 9 is a perspective view thereof, showing the portable notebook screen splitter in a closed state;

FIG. 10 is an enlarged detail view taken from portion 10 of FIG. 1; and,

FIG. 11 is an enlarged detail view taken from portion 11 of FIG. 9.

The broken lines in the drawings represent the extents of the detail views and form no part of the claimed design.

1 Claim, 11 Drawing Sheets
